BED READING LAMP

Maurice Lanery and Otto Lang,
New York, N. Y.

Application July 25, 1946, Serial No. 686,079

5 Claims. (Cl. 240—4)

1

This invention relates generally to lighting fixtures. More particularly our invention is directed to an improved construction for reading lamps of the type adapted for use in reading in bed.

Bed reading lamps as heretofore constructed have long been a recognized source of annoyance and conflict, in cases where two persons occupied the same bed. When one person wished to read while the other desired to sleep, the light rays from the lamp would annoy the sleeper. It is therefore one of the principal objects of our invention to provide a bed reading lamp of the character described which shall be so constructed and arranged as to avoid the above described disadvantages inherent in prior constructions of bed reading lamps and which at the same time shall be novel, simple in construction and highly efficient in use.

Another object of our invention is to provide a novel bed reading lamp which shall represent a general advance in the art.

Other objects of our invention will hereinafter be pointed out or will become apparent from the description to follow.

In the accompanying drawings,

Fig. 1 is a perspective view of a bed reading lamp constructed and arranged in accordance with our invention and illustrating its effective use;

Fig. 2 is an enlarged cross-sectional view taken substantially along the line 2—2 of Fig. 1;

Fig. 3 is a cross-sectional view taken substantially along the line 3—3 of Fig. 2;

Fig. 4 is a bottom plan view thereof; and

Fig. 5 is an enlarged cross-sectional view taken substantially along the line 5—5 of Fig. 2.

Referring now in detail to the drawings we have shown a bed reading lamp constructed and arranged in accordance with our invention and comprising a casing 10, which may be of metallic or other suitable opaque material. The said casing 10 may be rectangular in shape, as shown, and composed of a top wall 11, end walls 12 and 14, a front wall 15 and a rear wall 16, and open at the bottom. The said top, end, front and rear walls of the casing may be integrally joined, as shown, to render the joints light-proof, so as to normally permit the light rays from within the casing to escape only through the bottom opening.

Mounted within the casing 10, and fixed to the end wall 12 thereof is an electric lamp socket S of any well known standard type, adapted to receive therein a suitable lamp L. The said socket S may be retained in place by a threaded bushing 20 threadedly engaged in the base 19 of the socket and passing through an opening 21 in the wall 12. A nut member 22 on the bushing 20 will lock the socket against the said wall 12.

It is noted that the lamp L extends inwardly of the casing in a longitudinal direction away

2

from the wall 12, to a point beyond the center of said casing. A suitable wire 23, connected to the socket S and passing through the bushing 20 to the outside of the casing, leads to a suitable source of electric current. A switch 24 controls the lighting of the lamp.

In accordance with our invention we provide a light shield 30 which is pivotally mounted on the casing 10 in the manner and for the purpose 10 soon to be described.

The said light shield 30 comprises a pair of triangular shaped spaced apart side walls 31 and 32, and a rectangular shaped bottom wall 33. The said walls 31, 32 and 33 may be integrally joined, as shown, to prevent light leakage at the points of juncture. The wall 31 is so disposed as to lie closely adjacent the wall 15 of the casing and the wall 32, to lie closely adjacent the inner surface of the wall 16. The wall 31 is pivotally connected to the wall 15 by a suitable pivot 34 and the wall 32 is pivotally connected to the wall 16 by a suitable pivot 35.

The light shield 30 is of such size that the inner transverse edge 33a thereof will contactively engage the inner surface of the wall 14 of the casing at its free edge 14a. As clearly noted in Fig. 3 of the drawings the edge 33a of the light shield 30 is beaded or curved inwardly and the edge 14a of the casing wall 14 is correspondingly inwardly curved to prevent light leakage when the light shield is pivotally moved to one of its effective shielding positions.

It is noted that the location of the pivots 34 and 35 with respect to the position and location of the sockets is considered one of the important elements of our invention for the following reasons:

Assuming that a situation occurs where the person designated by the letter A in Fig. 1 desires to read while the person designated by the letter B desires to sleep. In that case the light shield 30 is pivotally moved about the pivots 34 and 35 as an axis to assume the effective position shown in Figs. 1 and 3. In such position it is noted that none of the light rays emanating from the lamp L is permitted to shine on the person B; the said rays being all directed through the opening in the casing to the right of the light shield and to furnish all light to the book of the reading person A. If on the other hand the situation was reversed and the person B desired to read while the person A was asleep, the light shield 30 may be pivotally rotated in a counter clockwise direction, as viewed from Fig. 3 of the drawings, to the dotted line position 30'. In this last named position A will be shielded from the light rays of the lamp while B will get the full benefit of the light for reading.

It is noted that the location of the pivots 34 and 35 are critically arranged so that when the light

shield 30 is pivotally moved to the position 30' as just described, the corner 33b will abut the socket S at a point beyond the inner extremity of the lamp L so as to provide against light passing to the sleeping person A.

Should the occasion arise when both persons A and B desire to read at the same time, the location of the pivots 34 and 35 are such that the light shield 30 may be pivotally moved in a clockwise direction to the dotted line position indicated by the numeral 30'' within the casing. In this last named position, it is noted that the light shield 30 will be entirely hidden from view and this is the position which may be employed when the bed reading lamp is not in effective use, so as to present the appearance of the usual bed lamp.

In accordance with our invention, as above described the light shield 30 is preferably mounted on the casing 10 in such a manner that there will be frictional contact therebetween whereby the said light shield will be maintained in any desired angularly rotated position about the pivots 34 and 35. One such means of frictional mounting is shown in the drawings and illustrated in detail in Fig. 5 thereof. As noted, the pivots 34 and 35 may be made in the form of screw members with the heads 34a and 35a thereof contactively engaging the outer surfaces of the casing walls 15 and 16 respectively. A nut 38 threadedly received on the pivot 34 contactively engages the inner surface of the light shield wall 31, while a nut 39 threadedly received on the pivot 35 contactively engages the inner surface of the light shield wall 32. Between the said walls 15 and 31 and between the said walls 16 and 32 are interposed resilient members 40 surrounding the pivots 34 and 35. The amount of resilient friction desired may be adjusted by the pivots and nuts 34, 35 and 38, 39.

For convenience in removably attaching the bed reading lamp of our invention to the headboard of a bed we provide the following construction:

Mounted on the wall 14 of the casing 10 in axial alignment with the bushing 20 is a shaft member 42 having a threaded outwardly extending portion. Rotatably mounted on the shaft 42 and bushing 20 is a bail member 45 comprising the side arms 43 and interconnecting cross bar 44. Permanently attached to the cross bar 44 are a pair of resilient hooks 48 adapted to snap over the top edge of the headboard 50 of the bed as clearly shown in Figs. 1 and 2 of the drawings. A nut 46 on the member 42 acting in cooperation with the nut 22 on the bushing 20 serve to frictionally hold the bail member 45 in any desired angular position.

In accordance with the provisions of the patent statutes, we have herein described the principle and operation of our invention, together with the construction which we now consider to represent the best embodiment thereof, but we desire to have it understood that the construction shown is only illustrative and that the invention can be carried out by other means. Also, while it is designed to use the various features and elements in the combinations and relations described, some of these may be altered and other omitted without interfering with the more general results outlined, and the invention extends to such use.

Having described our invention, what we claim and desire to secure by Letters Patent is:

1. A bed reading lamp of the character described comprising a longitudinal box-like casing open at the bottom thereof, an electric socket adapted to receive a lamp therein, means for

mounting said socket within said casing, a light shield member, means for mounting said light shield member on said casing for pivotal movement on an axis transverse to the longitudinal axis of said casing whereby it may be manually movable to a position to shield selected portions of the said open bottom against light passing therethrough from the lamp within the casing and means for removably mounting said casing on a bed.

2. A bed reading lamp of the character described comprising a casing having a top wall, a front wall, a rear wall, end walls and being open at the bottom, an electric socket adapted to receive a lamp therein, means for mounting said socket on one of said end walls of said casing whereby the said lamp will be disposed within said casing, a channel-shaped light shield member comprising a pair of aligned, spaced triangular shaped side walls and an interconnecting rectangular shaped bottom wall and means for rotatably mounting said light shield member on said casing whereby to block off certain selected portions of said open bottom of said casing from the light of said lamp for the purposes set forth.

3. A bed reading lamp of the character described comprising a casing having a top wall, a front wall, a rear wall, end walls and being open at the bottom, an electric socket adapted to receive a lamp therein, means for mounting said socket on one of said end walls of said casing whereby the said lamp will be disposed within said casing, a channel-shaped light shield member comprising a pair of aligned, spaced triangular shaped side walls and an interconnecting rectangular shaped bottom wall and means for rotatably mounting said light shield member on said casing whereby to block off certain selected portions of said open bottom of said casing from the light of said lamp for the purposes set forth, said last named means comprising a first pivot passing through said front wall of said casing and the adjacently disposed side wall of said light shield member, and a second pivot passing through said rear wall of said casing and the adjacently disposed side wall of said light shield member.

4. A bed reading lamp according to claim 3 in which the said light shield member is so constructed and arranged that the same may be rotatably moved to an ineffective position wholly within said casing and to a position whereby to permit the light rays from said lamp to pass freely through said open bottom of said casing.

5. A bed reading lamp according to claim 3 in which a resilient member is interposed between each of said adjacently disposed side walls of said light shield member and said front and rear walls of said casing.
